Atty.*

UNITED STATES PATENT OFFICE.

CLARENCE B. BISHOP, OF CHICAGO, ILLINOIS, ASSIGNOR TO THE NATIONAL SLIDING HINGED SCREEN COMPANY, OF SAME PLACE.

SLIDING SCREEN, DOOR, &c.

SPECIFICATION forming part of Letters Patent No. 451,681, dated May 5, 1891.

Application filed April 28, 1890; Serial No. 349,728. (No model.)

To all whom it may concern:

Be it known that I, CLARENCE B. BISHOP, a citizen of the United States, residing at Chicago, Cook county, Illinois, have invented a new and useful Improvement in Sliding Screens, Doors, &c., of which the following is a specification.

It is often desirable or even essential that sliding screens, windows, doors, and similar structures should be capable of being opened outward or inward as though hung upon hinges like a door or gate; and it is the object of my invention to provide means whereby screens, doors, &c., may be thus opened while still remaining capable of sliding up and down upon or in guides or ways; and the invention consists in the features and details of construction hereinafter described and claimed.

I shall illustrate and describe in the drawings and specification and also claim in the claims hereof my improvement as applied to a window-screen; but I desire it be definitely understood that I do this simply for the sake of brevity and convenience; and not with the intention of limiting myself to this use alone, since I am fully aware that the devices hereinafter described may be applied with equal efficiency to a sliding door, window, or similar structure, and I contemplate so applying them.

In the drawings, Figure 1 represents a vertical exterior elevation of a window provided with one of my improved screens; Fig. 2, a horizontal section on the line 2 2 of Fig. 1, looking in the direction of the arrows, the position of the screen when open being indicated in dotted lines; Fig. 3, a central section through the upper left-hand corner of the screen, showing the construction of one of the spring-hooks; Fig. 4, a perspective view of one of the eyes or sockets, the strip on which the screen slides being indicated in dotted lines; Fig. 5, a perspective view of the spring-hook removed from the screen, and Fig. 6 a vertical elevation of the left-hand edge of the screen.

A represents the screen; B, the upper window-sash; C, the lower sash, and D and E the strips on which the screen slides.

The screen A is made of any suitable dimensions and material and, except as hereinafter

described, in the ordinary well-known manner. To either side of the casing of the window in which the screen is to be used is fastened a strip of suitable material, preferably wood, and preferably extending from top to bottom of the window to allow the screen to be placed in any position therein. The screen is provided, as shown, with a groove D' E' along each of its edges adapted to engage with the strips D and E. These strips are also preferably grooved in a reverse direction to the grooves in the screen, as shown in Figs. 2 and 4. At suitable points in the groove on one side of the screen (in the drawings this is shown as the left-hand side, but it may be either side, as desired) are placed spring-hooks F. There may be any number of these hooks desired; but I prefer to use two. The construction of one of these hooks is more particularly shown in Fig. 5. It consists of two rods or shanks f', running substantially at right angles to each other, and connecting, as shown, with the portion f'', which is preferably flattened. A hole or socket is bored, as shown in Fig. 3, in the screen, of suitable shape and dimensions to receive the shank f', a larger tube or chamber being preferably constructed to receive a spring G, which abuts, as shown, against the inner side of the flattened portion f'', forcing it outward. A plate H is preferably fastened over the hole in the screen, the spring-hook being provided with shoulders h, contacting with the inner side of this plate to prevent the hook from being forced entirely out of the screen by means of the spring. The plate is provided with an opening of suitable size to receive and fit the flattened portion f''.

At suitable points in the strip D are fastened eyes or sockets I, provided with holes i of suitable dimensions to engage with the portion f of the spring-hook F, there being of course an equal number of sockets and hooks.

The device operates as follows: To insert the screen the groove D' is passed over the strip D and the screen pressed toward the left. This forces in the spring-hooks F, compressing the springs G. The right-hand edge of the screen may then be swung around until the groove E' comes into line with the strip

E. The pressure on the screen being then released, the resiliency of the springs G will force the spring-hooks F against the strip D, carrying the screen slightly toward the right 5 and bringing the groove E' into engagement with the strip E. The screen may then be slid up and down upon the strips D E, and is held in any position through the pressure of the hooks F against the strip D. If it be de-
10 sired to open the screen, it is slid down in the window, the hooks F engaging as the screen descends with the sockets I. The screen is then pressed toward the sockets, compressing the springs and releasing the groove E' from 15 the strip E, and may then be swung open, as desired, being supported by means of the hooks F and sockets I. One position of the screen when opened is indicated by the dotted lines in Fig. 2. To close the screen, press 20 it toward the left sufficiently to allow the groove E' to engage with the strip E, after which the screen may be slid up and down, as desired. Any other form of spring may be used, as desired, to force out the hooks F, the 25 flattened portion of such hooks may be omit-

ted, any other suitable guides may be employed in place of the strips D and E, and other similar changes of form and construction may be made without departing from the spirit of my invention, the gist whereof consists in so constructing a screen, door, or similar structure as to enable it to both slide up and down and swing open. 30

I claim—

The combination of a screen A, having 35 grooves D' and E' and hooks forced out by springs, strips D and E, and sockets I, adapted to engage with the hooks F, whereby the screen may be slid up and down upon the strips, being held in position by the pressure 40 of the hooks, or, after being pressed to one side to disengage the groove E from strip E', may be swung open, being supported when open by means of the hooks and sockets, substantially as described.

CLARENCE B. BISHOP.
